UNITED STATES PATENT OFFICE.

FRANKLIN H. SMITH, OF YONKERS, NEW YORK, ASSIGNEE, BY MESNE ASSIGNMENTS,
TO GOLD CAR HEATING & LIGHTING COMPANY, OF NEW YORK, N. Y., A CORPORA-
TION OF NEW YORK.

ELECTRIC HEATER.

1,040,043.

Specification of Letters Patent.

Patented Oct. 1, 1912.

Application filed May 10, 1911. Serial No. 326,208.

To all whom it may concern:

Be it known that I, FRANKLIN H. SMITH, a citizen of the United States, residing at Yonkers, in the county of Westchester and State of New York, have invented certain new and useful Improvements in Electric Heaters, of which the following is a specification.

My invention relates to electric heaters, particularly to such type of electric heater as is adapted for the heating of surface cars.

In heaters of this type difficulty has been experienced in cases where the heating apparatus got out of order, by reason of the fact that the entire car was thereby disabled, or if it was used it was used without the benefit of the heating apparatus.

My invention therefore has for its object to provide a heating apparatus wherein a number of heaters are combined within each heating apparatus, and they are so constructed that each of the heaters may be removed and replaced by another without disturbing the other heaters in the casing.

I have so constructed the said apparatus that this operation may be performed expeditiously. By this means the utility of the rolling stock of railroads is increased by reason of the fact that its usefulness is not impaired by delay in repairing the heating apparatus.

A desirable form in which my invention may be embodied is illustrated in the accompanying drawings, wherein,—

Figure 1 illustrates an elevation of a car seat showing the manner in which my heaters are used; Fig. 2 is a longitudinal section of one of the heaters on the line 2—2 of Fig. 3; Fig. 3 is a cross-section of a heater on the line 3—3 of Fig. 2; Fig. 4 is a longitudinal fragmentary section on the line 4—4 of Fig. 3; Fig. 5 is an external side view of an end block; Fig. 6 is a detail perspective view of a supporting block employed to assist in supporting the individual heaters.

My invention in the particular form in which it is illustrated in the accompanying drawings, employs a pair of end blocks A, each of which has slots a , a^1 a^2 which are adapted to support the individual heaters. These heaters are designated B, and are shown as being three in number. They are all of the same construction, and are illus-

trated as being formed of a core b of suitable insulating material, for which porcelain is well adapted. This I prefer to provide with a hollow center b^1 and perforations as at b^2 , and to mount thereon a heating wire b^3 which is in the form of a coil 60 helically wound thereon and received in peripheral grooves upon the core, the particular construction of said core however forms no part of this present invention.

The supporting rod b^4 extends through the hollow center of each of the heaters, and at its end passes into a perforated block C, whereon it may be held by nuts c . The rod is useful for two purposes. In the first place, to hold the heater together in case 70 the porcelain core of the same is constructed of several sections, as is usually the case, and in the next place to assist in maintaining each heater in position in the casing. The blocks C are adapted to fit the grooves a , a^1 or a^2 , and when the heater B is secured to a pair of the said blocks and the same are seated in the said grooves, it is secured in place by suitable means. Such means as illustrated comprise a nut D having a hollow 80 internally threaded shank d which passes through a perforation a^3 in the end plate and is received upon the threaded end of the supporting rod b^4 . A lock washer d^1 may be provided if desired. It will be observed that the nuts D will compensate for any unevenness in position of one or the other of the end plates A, by reason of the fact that each heater may be adjusted lengthwise of the casing until it is in a position where it will be engaged by each of the nuts D.

Suitable conductors b^5 are connected to the coils b^3 and pass through openings a^4 in the end plates. As many openings are provided as there are heaters within the casing, so that each heater is provided with an independent electrical connection, and these are separate from one another. The rods b^4 are preferably square, and the same 100 is true of the aperture in the block C through which the rods pass, as indicated in Fig. 6 at c^1 . The opposite side of the said block, shown in dotted lines in said figure, has a round aperture, which I shall 105 designate c^2 , and which is made of this shape to accommodate the round shank d of nut D.

The casing E within which the said heaters are contained is represented as of substantially half round shape in cross-section, although this shape is not material, and as mounted it extends lengthwise of the car and is arranged beneath a seat F. The slots a , a^1 , a^2 are directed toward the front of the seat, in such position that when the front plate e is removed, any of the heaters may easily be taken out from the casing without disturbing the others. The front plate e has the usual perforations to permit the passage of the heated air. The casing E may if desired be provided with an internal lining in the form of a sheet of asbestos e^1 .

The several heaters B, of which three are illustrated, may be placed in the several grooves a , a^1 , a^2 , and their electrical connections b^5 at each end pass through the holes a^3 in the end plates and are attached to wires outside which are not illustrated. If for any reason all of the heaters are to be removed from the casing, the end blocks 25 A may be slid out of the channels e^2 in which they are mounted in the casing. Such channels extend around the interior of the casing at each end and are of trough shape and adapted to receive the end blocks. The 30 end blocks are slightly beveled upon their interior inner sides at a^5 for use in assembling. In case one of the said heaters should be disabled, or for any reason it is desired to remove it and replace it by another, its wires b^5 may be disconnected outside of the 35 end plates from the electrical supply wires and drawn through the perforations a^4 in the said end plates, whereupon the blocks C will easily slide out of the grooves in the 40 end plates.

I have in the accompanying drawings illustrated one form in which my invention may be embodied, and which is the best form now known to me, and I have in the 45 foregoing description described this form. It will be apparent, however, that the invention is not necessarily confined to the particular shape and construction illustrated and described, as equivalent devices 50 may be used and other changes made therein within the limits of the appended claims.

I claim as my invention:

1. In an electric heater, a casing, oppositely disposed end plates adapted to close 55 the ends of said casing, a plurality of electric heaters lying within said casing and mounted in said end plates so as to be independently removable, and an independent electrical connection to each heater.

60 2. In an electric heater, an open front casing, a plurality of heater supports disposed with relation to said casing so as to support electric heaters in said casing, a plurality of electric heaters lying within 65 said casing and mounted in said supports

so as to be independently removable, and an independent electrical connection to each heater.

3. In an electric heater, an open front casing, a heater support adapted to support a 70 heater in said casing, a plurality of heaters lying within said casing and mounted in said support so as to be independently removable, and independent electric connections to each heater.

4. In an electric heater a casing, slotted end plates secured thereto, each of said slots adapted to hold a heater and to permit its removal independently of the other heaters, and a heater in each of said slots having an 80 independent electrical connection.

5. In an electric heater, a casing, slotted end plates secured thereto, each of said slots adapted to hold a heater and to permit its removal independently of the other heaters, 85 and means for mounting the heaters in said slots comprising blocks secured to each end of the heater and adapted to slide in said slots.

6. In an electric heater a casing, slotted end plates secured thereto, each of said slots adapted to hold a heater and to permit its removal independently of the other heaters, means for mounting the heaters in 90 said slots comprising blocks secured to each end of the heater and adapted to slide in said slots, and threaded means arranged externally of said end plates and adapted to engage threaded portions of each end of 95 each heater and to secure same in place.

7. In an electric heater, a casing, a plurality of heaters therein each comprising an insulating core, a supporting rod and a conductor, end plates in said casing each provided with slots for said heaters, permitting the independent removal of each of 100 said heaters, each of said end plates perforated to receive a threaded nut adapted to engage the threaded end of said supporting rod, whereby said heater may be supported 110 independently of irregularity in the position of the end plates.

8. In an electric heater, a plurality of heaters each comprising an insulating core and a conductor, together with a supporting rod extending through a perforation in said core, blocks on each end of said rod and means for adjustably securing the same thereon, end plates provided with slots adapted to receive said blocks and to hold 115 a heater in heating position, and to permit the removal of any of said heaters without distributing the others.

9. In an electric heater, a plurality of heaters each comprising an insulating core and a conductor, together with a supporting rod extending through a perforation in 120 said core, blocks on each end of said rod and means for adjustably securing the same thereon, end plates provided with slots and 125

- a casing adapted to receive said end plates, said slotted end plates adapted to receive said blocks and to hold a heater in heating position and to permit the removal of any 5 of said heaters without disturbing the others.
10. In an electric heater, a casing having internal channels, grooved end plates removably mounted in said channels, and a 10 plurality of heating units in said casing each mounted in a groove in said end plates so as to be independently removable.
11. In an electric heater, a casing having internal channels, grooved end plates removably mounted in said channels, a plurality 15 of heating units in said casing each having an insulating core, a conductor thereon, a supporting rod, and blocks upon said rod each adapted to slide in a groove in one of said end plates so as to permit the independent removal of its attached heater.
12. In an electric heater, a casing having internal channels, grooved end plates removably mounted in said channels, a plurality 20 of heating units in said casing each having an insulating core, a conductor thereon, a supporting rod, blocks upon said rod each adapted to slide in a groove in one of said end plates so as to permit the independent removal of its attached heater, threaded nuts extending through said end 25
- plates and engaging the threaded ends of said rods, and said conductors passing through individual perforations in said end plates.
13. In an electric heater, a casing having grooved end plates, and a plurality of heating units in said casing each mounted in a groove in said end plates so as to be independently removable.
14. In an electric heater, an open front casing, a heater support in said casing having a plurality of supporting slots, a plurality of heaters mounted one in each of said slots so as to be independently removable, 40 and independent electric connections to each heater.
15. In an electric heater, a casing, a plurality of supports in said casing, each having a plurality of horizontal oppositely disposed slots opening toward the front of said casing, an electrical heater mounted in each set of opposite slots, and having independent electrical connections whereby each heater may be independently removed.
- In witness whereof, I have hereunto signed my name in the presence of two subscribing witnesses.

FRANKLIN H. SMITH.

DISCLAIMER.

1,040,043.—*Franklin H. Smith, Yonkers, N. Y.* ELECTRIC HEATER. Patent dated October 1, 1912. Disclaimer filed May 2, 1917, by the assignee, *Gold Car Heating & Lighting Company*.

Enters this disclaimer—

“To that part of the claim in said specification which is in the following words, to wit:

“5. In an electric heater, a casing, slotted end plates secured thereto, each of said slots adapted to hold a heater and to permit its removal independently of the other heaters, and means for mounting the heaters in said slots comprising blocks secured to each end of the heater and adapted to slide in said slots.

“13. In an electric heater, a casing having grooved end plates, and a plurality of heating units in said casing each mounted in a groove in said end plates so as to be independently removable.”
